ABSTRACT

A new garden rose plant of the Compact Floribunda class which has abundant, red flowers and attractive foliage. This new and distinct variety has shown to be uniform and stable in the resulting generations from asexual propagation.

2 Drawing Sheets

1

Botanical designation: *Rosa hybrid*.
Variety denomination: 'Poulpal072'.

SUMMARY OF THE INVENTION

The present invention constitutes a new and distinct variety of rose plant which originated from a controlled crossing between the female seed parent, an unnamed seedling, and the male pollen parent, also an unnamed seedling. Both of the parent varieties are non-patented.

The two parents were crossed during the summer of 2008 and the resulting seeds were planted in a controlled environment in Fredensborg, Denmark. The new variety, named 'Poulpal072', originated as a single seedling from the stated cross.

The new variety may be distinguished from its male pollen parent and female seed parent primarily by the following characteristics. The male pollen parent plant has a growth height of 60 cm, while the new variety has a growth height of 40 cm. The female seed parent plant has pink flowers while the new variety has red flowers.

The objective of the hybridization of this rose variety was to create a new and distinct variety with unique qualities, such as:

1. Uniform and abundant red flowers;
2. Vigorous, but compact growth when propagated on its own roots;
3. Exceptional disease resistance.

This combination of qualities is not present in previously available commercial cultivars of this type, known to the inventor, and distinguish 'Poulpal072' from all other varieties of which we are aware.

As part of the rose development program, Mogens N. Olesen germinated the seeds from the aforementioned

2

hybridization during winter of 2008 and conducted evaluations on the resulting seedlings in a controlled environment in Fredensborg, Denmark. 'Poulpal072' was selected in the spring of 2009 by the inventor as a single plant from the progeny of the aforementioned hybridization.

Asexual reproduction of 'Poulpal072' by rooted cuttings was first done by Mogens N. Olesen in the nursery in Fredensborg, Denmark in July, 2009. This initial and other subsequent asexual propagations conducted in controlled environments have demonstrated that the characteristics of 'Poulpal072' are true to type and are transmitted from one generation to the next.

DESCRIPTION OF THE DRAWING

The accompanying color illustrations show as true as is reasonably possible to obtain in color photographs of this type, the typical characteristics of the buds, flowers, leaves, and stems, of 'Poulpal072'.

Specifically illustrated in FIG. 1 of the drawings are a cluster of flower buds on a bare branch, open flowers viewed from the side and above, flower petals detached, and sepals detached showing reproductive flower parts.

Specifically illustrated in FIG. 2 of the drawings are bare stems and leaves. Plants shown are 2 years of age.

DETAILED DESCRIPTION OF THE VARIETY

The following is a description of 'Poulpal072', as observed in its growth in a field nursery in Marion County, Oreg. Observed plants are 2 years of age, and were grown on their own roots. Color references are made using The Royal Horticultural Society (London, England) Colour Chart, 2001, except where common terms of color are used.

For a comparison, several physical characteristics of the rose variety 'Poulpal020', U.S. Plant Pat. No. 18,121 are compared to 'Poulpal072' in Chart 1.

CHART 1

	'Poulpal072'	'Poulpal020'
Petal Count	40	80
Flower Diameter	100 mm	50 mm
General Tonality of Flower Color	Red Group 53A	Red 46A

FLOWER AND FLOWER BUD

Blooming habit: Continuous.

Flower bud:

Size.—Upon opening, 29 mm in length from base of receptacle to end of bud. Bud diameter is 15 mm.

Bud form.—Urceolate.

Bud color.—As sepals divide petals are Red Group 46A.

Sepal inner surface.—Color: Yellow-Green Group 144B, with intonations of Greyed-Red Group 180A. Surface: Lightly pubescent.

Sepal outer surface.—Color: Yellow-Green Group 144A with strong intonations of Greyed-Orange Group 166A. Texture: Smooth.

Sepal shape.—Apex: Cirrhose. Base: Flat at union with receptacle.

Sepal margin.—Margins have moderate foliaceous appendages on three of the five sepals.

Sepal size.—25 mm long, 9 mm wide.

Receptacle.—Texture: Smooth. Size: 10 mm in height, 10 mm wide. Color: Yellow-Green Group 144A, with intonations of Greyed-Purple Group 187B. Shape: Campanulate.

Pedicel.—Surface: Smooth. Length: 35 to 50 mm. Diameter: 3 mm on average. Color: Yellow-Green Group 144A with strong intonations of Greyed-Purple Group 187B. Strength: Strong.

Peduncle.—Length: 2 to 8 to cm. Diameter: About 4 mm. Color: Yellow-Green Group 145A with strong intonations of Greyed-Purple Group 187B. Texture: Smooth.

Flower bud development: Flower buds are borne in clusters of 3 or single.

Flower bloom:

Fragrance.—Light floral.

Duration.—The blooms have a duration on the plant of approximately 10 days. Petals fall cleanly away from plant after flowers have fully matured.

Size.—Flower diameter is 100 mm when open. Flower depth is 40 mm.

Flower shape.—Quartered-rosette, very double, with many overlapping petals packed into quarter sections.

Shape of flower, side view.—The upper portion is flat. The lower portion is a flattened convex.

Petalage: Under normal conditions, flowers have about 40 petals.

General tonality of flower: Open flowers are Red Group 53A.

Petal color:

Upon opening, outer and inner petals.—Upper surface: Red Group 53A and Red 53B. Lower surface: Red-Purple Group 58B. Petal streak: On both surfaces, occasional streak of White Group 155A.

Basal petal spots, upon opening.—Upper surface: Yellow Group 8A. Lower surface: Yellow Group 4D.

After opening, outer and inner petals.—Upper surface: Red Group 53A and Red 53B. Lower surface: Red-Purple Group 58B. Petal streak: On both surfaces, occasional streak of White Group 155A.

Basal petal spots, after opening.—Upper surface: Yellow Group 8A about 7 mm in length. Lower surface: Yellow Group 4D about 7 mm in length.

15 Petals:

Petal reflex.—Light.

Margin.—Entire and uniform. No undulations.

Shape.—Broad and elliptic. Apex shape: Rounded. Base shape: Acute.

Size.—46 mm (l)×48 mm (w).

Texture.—Smooth.

Thickness.—Average.

Petaloids:

Size.—35 mm (l) by 32 mm (w).

Quantity.—5 to 9.

Shape.—Elliptical with an acute base and rounded apices.

Color.—Red Group 53A on the upper surface, with a petaloid spot at the base Yellow Group 8A. Red-Purple Group 58B at the undersurface, with a spot of Yellow Group 4D at the base. Occasional streaks of 155A.

Reproductive flower parts:

Pollen.—None observed.

Anthers.—Size: 3 mm in length. Color: Yellow Group 8A. Quantity: 55 on average.

Filaments.—Color: Yellow Group 16A. Length: 5 to 7 mm.

Pistils.—Length: 4 mm. Quantity: 25 on average.

Stigmas.—Color: Greyed-Yellow Group 160D.

Styles.—Color: Green-White Group 157A.

Location of stigmas.—Inferior in location relative to the length of the filaments and the height of the anthers.

Hips.—None Observed.

PLANT

50 Plant growth: Upright, bushy. Plants are 40 cm in height, and 40 cm wide.

Stems:

Color of juvenile growth.—Yellow-Green Group 144A with intonations of Greyed-Red Group 178C.

Color of mature growth.—Yellow-Green Group 146B.

Length.—Canes are about 18 to 20 cm from the base of the plant to the flowering portion.

Diameter.—About 4 mm.

Internodes.—On mature canes about 30 mm between nodes.

Surface texture.—Young wood: Smooth. Older wood: Smooth.

Long prickles:

Incidence.—5 prickles per 10 cm of stem.

Size.—Average length of prickles on mature stems is 7 mm.

Shape.—Upper portion is linear. Lower portion is concave.

Color.—Juvenile prickles: Greyed-Yellow Group 160A and Greyed-Orange Group 166B. Mature prickles: Greyed-Orange Group 166B.

5

Plant foliage:

Compound leaf.—110 mm (l)×85 (w).

Quantity.—2 to 3 leaves per 10 cm of stem.

Leaf bearing angle to the stem.—45 degrees.

Color of juvenile foliage.—Upper side: Yellow-Green Group 144A, with marginal intonations of Greyed-Purple Group 183A. Lower side: Yellow-Green Group 146D with intonations of Greyed-Purple Group 183A.

Color of mature foliage.—Upper side: Yellow-Green Group 147A. Lower side: Yellow-Green Group 147C.

Plant leaves and leaflets:

Stipules.—Size: 13 mm long, 4 mm wide. Quantity: 2 per compound leaf. Shape: Linear, slightly broad based with outward extending apices. Margins: Finely serrated. Color: Yellow-Green Group 144A.

20

Petiole.—Length: 32 mm. Diameter: 2 mm. Upper surface color: Yellow-Green Group 144A. Lower surface color: Yellow-Green Group 144A.

25

Rachis.—Length: 30 mm. Upper surface color: Yellow-Green Group 144A. Lower surface color: Yellow-Green Group 144A.

Leaflet.—Quantity: Normally 5 leaflets. Margins: Serrated. Size: Terminal leaflets are about 40 mm long, 30 mm wide. Shape: Generally elliptical. Base: Rounded. Apex: Mucronate. Texture: Smooth. Thickness: Average. Arrangement: Odd pinnate. Venation: Reticulate. Glossiness: Not glossy.

10 *Disease resistance*: Above average resistance to powdery mildew *Sphaerotheca pannosa*, downy mildew *Peronospora sparsa*, rust *Phragmidium* sps., black spot *Diploropon rosae*, and *Botrytis cinerea* under normal growing conditions.

15 *Cold hardiness*: The variety is tolerant to USDA Cold Hardiness Zone 6.

Heat tolerance: The variety has been found to be suitable for climate conditions found in the American Horticulture Society heat zone 7.

I claim:

1. A new and distinct variety of rose plant of the Compact Floribunda rose class named 'Poulpal072', substantially as illustrated and described herein, due to its abundant red flowers, disease resistance, and extended period of bloom.
